RACK FOR A GLASS CONTAINER

Guy Vrignaud, Grenoble, France, assignor to Allibert
Exploitation Societe Anonyme, Puteaux, France

Filed Nov. 6, 1974, Ser. No. 521,495

Claims priority, application France May 6, 1974

Term of patent 14 years

Int. Cl. D19—02

U.S. Cl. D19—75

FIG. 1

FIG. 2

FIG. 3

FIG. 5

FIG. 4

FIG. 6

FIG. 1 is a perspective view of a rack for a glass container showing my new design;

FIG. 2 is a top plan view thereof;

FIG. 3 is a bottom plan view thereof;

FIG. 4 is a front elevational view thereof;

FIG. 5 is a left end elevational view, the opposite end being a mirror image thereof; and

FIG. 6 is a rear elevational view thereof.

I claim:

The ornamental design for a rack for a glass container, as shown and described.
